SAMUEL A. THOMPSON, OF NEW YORK, N. Y.

COMBINED BASE AND RECEPTACLE FOR TOY TYPEWRITERS OR THE LIKE

Application filed May 4, 1931. Serial No. 535,057.

This invention relates to a combined base and receptacle which, while not necessarily limited to such use, is particularly designed as a base for toy typewriters, such as those disclosed in my prior United States Letters Patents, Nos. 1,138,427 and 1,521,408.

The outstanding object of the present invention is to provide a combined base and receptacle which embodies but few inexpensive and simple parts capable of economical production and assembly with each other and with the typewriter or other article with which it is associated.

More specifically, the invention resides in an article of the indicated character which includes a hollow open-ended body forming a supporting base for slidably receiving and housing a drawer therein, and in which said body is so fashioned as to afford a steady supporting base which will not scratch or otherwise mar the supporting surface upon which it is rested.

The invention further resides in a drawer structure for use in connection with the base which is so fashioned as to avoid buckling and catching of the edge of the drawer in the ends of the base, and which structure permits of the production of the drawer from an inexpensive material while possessing the requisite ruggedness.

With the above recited and other objects in view, reference is had to the following description and accompanying drawing, in which there is exhibited one example or embodiment of the invention, while the claims define the actual scope of the same.

In the drawing:

Figure 1 is a perspective view of the base with the drawer in closed condition, and illustrating the base detached from the typewriter or other article which it is designed to support.

Figure 2 is a similar view of the drawer completely removed from the base.

Figure 3 is an enlarged longitudinal sectional view through the base, taken approximately on the line indicated at 3-3 in Figure 1 and illustrating the drawer partially projected therefrom.

Figure 4 is an enlarged transverse sectional

view taken approximately on the line 4-4 of Figure 1.

Referring to the drawing by characters of reference, the combined base and receptacle includes a body designated generally by the reference character A and a drawer designated generally by the reference character B. The body A includes a top wall 10 and integral depending side walls 11, which walls are formed at their lower ends with inwardly directed marginal flanges 12, also preferably formed integral with the side walls 11. The walls 10 and 11 and flanges 12 are preferably fashioned from a cheap grade thin gauge of sheet metal and at the juncture of the flanges 12 with the side walls 11, said side walls are preferably offset laterally and outwardly as at 13, to present internal longitudinally extending guide grooves 14. The body A is completed by means of a bottom wall 15, which is preferably formed of cardboard or analogous material having bifurcated opposite side edges presenting upper and lower furcations 16 and 17. The bifurcated side edges may be variously produced, either by constructing the bottom wall 15 of two or more plies or by slitting a single ply in a plane parallel to the upper and lower surfaces of the bottom wall. In any event, the furcations 16 and 17 are resilient to a degree sufficient to cause the same to grip the flanges 12 and hold the bottom wall in assembled relation with the remainder of the body without the necessity of additional fastening means. The width of the bottom wall 15 is such that when assembled with the remainder of the body the free edges of the upper furcations 16 snugly extend into the internal grooves 14 formed by the offset 13, thereby causing the downward deflection or offsetting of the lower furcations 17 to present supporting margins at the opposite sides for contact with a supporting surface upon which the base is rested. This affords a steadier support for the base than would be possible if the complete lower surface of the bottom wall rested upon the supporting surface. At the same time, the non-metallic material from which the bottom wall is constructed is such as to avoid scratching or

marring of the supporting surface. The body A as thus constructed is capable of being economically produced and assembled and is open at its opposite ends. The top wall 10 may 5 be formed with a series of apertures 18 for the reception of bendable tongues to facilitate the attachment of the typewriter or other article to be carried thereby.

The drawer B is formed in the ordinary 10 manner of a carton constructed from a single sheet of cardboard fashioned to provide an upper wall 20, a side wall 21, a lower wall 22 and overlapped adhesively secured portions defining the other side wall 23 and provided with integral end walls 24 having the tuck in flaps 23'. In the present instance, 15 however, the upper wall is provided with an enlarged rectangular central cutout 25, from the ends of which cutout portion integral pieces 26 are bent downwardly parallel to the end walls 24, and from the free lower ends 20 of which pieces 26 horizontal terminal slabs 27 extend toward the end walls to overlie the tuck in flaps 23'. This, obviously, braces and 25 strengthens the structure of the drawer adjacent its ends, while the juncture of the pieces 26 with the top wall 20 of the drawer presents a rounded edge 28, precluding buckling and interference with the closing movement of the drawer by catching of the edge 28 30 on the open ends of the body.

From the foregoing, it will thus be seen that a combined supporting base and receptacle has been devised which may be produced 35 economically and yet which possesses certain obvious advantages and attributes due to the particular structure thereof.

What is claimed is:

1. In a combined supporting base and receptacle, the combination of a hollow rectangular body open at its opposite ends and a rectangular drawer slidably received through said ends and snugly housed by said body, said drawer having an open upper 40 end provided with an inwardly extending continuous marginal flange and downturned flaps at the opposite ends of the drawer opening bearing respectively on the bottom of the drawer.
2. In a combined supporting base and receptacle, a hollow rectangular body open at its opposite ends and a rectangular drawer constructed from a single sheet of material cut, bent, folded and secured to provide a 45 top, bottom, side and end walls, the top wall having a central rectangular cutout defining a continuous inwardly extending marginal flange formed with downturned integral flaps at the opposite ends of the cutout to bear 50 against the bottom wall of the drawer whereby to brace the drawer structure transversely and to avoid buckling of the ends.
3. In a combined supporting base and receptacle of the indicated character, a hollow 55 open-ended body for slidably receiving and

housing a drawer, said base including a metallic top wall having integral depending side walls and integral inwardly directed flanges at the lower ends of said side walls and a non-metallic bottom wall having bifurcated 70 side edges receiving and frictionally engaging said side wall flanges.

4. In a combined supporting base and receptacle of the indicated character, a hollow open-ended body for slidably receiving and 75 housing a drawer, said base including a metallic top wall having integral depending side walls and integral inwardly directed flanges at the lower ends of said side walls and a non-metallic bottom wall having bifurcated 80 side edges receiving and frictionally engaging said side wall flanges, the lower furcations of the bifurcated edges of the bottom wall being downwardly offset to provide spaced parallel supporting ribs adjacent the 85 opposite sides of the base.

5. In a combined supporting base and receptacle of the indicated character, a hollow open-ended body for slidably receiving and 90 housing a drawer, said base including a metallic top wall having integral depending side walls and integral inwardly directed flanges at the lower ends of said side walls, said walls being laterally and outwardly offset at the juncture of the flanges thereof and a cardboard bottom wall having bifurcated 95 side edges straddling said side wall flanges and frictionally engaging the same with the upper furcations embraced by the lateral and outward offsets.

6. In a combined supporting base and receptacle of the indicated character, a hollow open-ended body for slidably receiving and 100 housing a drawer, said base including a metallic top wall having integral depending side walls and integral inwardly directed flanges at the lower ends of said side walls, said walls being laterally and outwardly offset at the juncture of the flanges thereof and a cardboard bottom wall having bifurcated 105 side edges straddling said side wall flanges and frictionally engaging the same with the upper furcations embraced by the lateral and outward offsets, the lower furcations being 110 downwardly offset to provide spaced parallel supporting ribs adjacent the opposite sides of the base.

Signed at New York, in the county of New York and State of New York, this 23 day of April, A. D. 1931.

SAMUEL A. THOMPSON.
